UNITED STATES PATENT OFFICE.

HUGO PAUL HAANEL, JR., OF ST. LOUIS, MISSOURI.

PIANOFORTE ATTACHMENT.

1,229,257.

Specification of Letters Patent. Patented June 12, 1917.

Application filed July 19, 1916. Serial No. 110,099.

To all whom it may concern:

Be it known that I, HUGO PAUL HAANEL, Jr., a citizen of the United States, residing at St. Louis, State of Missouri, have invented certain new and useful Improvements in Pianoforte Attachments, of which the following is a full, clear, and exact description, reference being had to the accompanying drawings, forming a part hereof.

10 My invention has relation to improvements in piano-forte attachments; and it consists in the novel features of construction more fully set forth in the specification and pointed out in the claims.

15 The present invention is directed to that class of attachments which may be exteriorly applied to the keyboard of a piano for a purpose to be hereinafter pointed out, and which may be readily detached when desired

20 without in any manner impairing the piano.

The object of the invention is to provide an instruction sheet or roll which shall wind on rollers in proximity to the keyboard, and in so doing designate by suitable pointers or

25 indicator strips, the notes to be struck by the performer. A further object is to give the performer (or student) instruction in the rudiments of piano-forte by means of appropriate markings on the sheet or roll; a

30 further object is to provide a piano-forte attachment whereby one who is not a skilled pianist may be enabled to play piano compositions without previous practice or instruction; a further object is to provide an

35 attachment for the purposes specified that may be readily controlled by the operator, and one that is simple in its construction, and possesses other advantages more particularly pointed out in a detailed description

40 of the invention in connection with the accompanying drawings in which—

Figure 1 is a perspective view of an upright piano-forte showing my invention applied thereto; Fig. 2 is a vertical cross-section

45 through the roll on the line 2—2 of Fig. 1, parts of the piano being shown dotted; Fig. 3 is a vertical longitudinal section of the bracket-casing on the line 3—3 of Fig. 4; Fig. 4 is an outside end elevation of

50 the bracket-casing with parts broken away; Fig. 5 is an inside end elevation of the

bracket-casing with parts broken away; Fig. 6 is a front elevation of the left-hand supporting bracket with parts broken away and with fragments of the rollers and sheet 55 mounted thereon; Fig. 7 is a cross-sectional detail of the speed regulating cam taken on the line 7—7 of Fig. 5; Fig. 8 is a plan of one of the rollers with the instruction sheet attached showing several of the pointers or 60 indicator strips thereon; and Fig. 9 is a vertical cross-section through the upper roller on the line 9—9 of Fig. 3.

Referring to the drawings, P represents an upright piano-forte to the sidearms A, A, 65 of which are clamped by means of screw-clamps C, C', the bracket B, and bracket-casing B' respectively, which have the rollers R, R', mounted between them, the roller R being in close proximity to the keyboard 70 K composed of the keys k, k, etc. S represents an indicator roll of suitable material secured and normally wound on the roller R, and adapted to be unwound therefrom and wound onto the roller R' upon passing the 75 hooks h, h, at each end of said roller through the perforated flaps e, e, of the roll S, and imparting rotation to the roller R' in a manner presently to be described. The roll S is provided throughout its extent with indicator strips or pointers p, p', punched from the body of the sheet M constituting the roll in such a manner that their free ends will be rearward with reference to the direction of travel of the roll as it winds on the roller R' 85 (Fig. 2). The rollers R, R' are provided at each end with spindles g, g, those of the roller R resting in the bearing 1 of the bracket B and bearing 1' of the casing B' 90 respectively.

The casing B' is provided with a removable wall or cover w, between which and the inner fixed wall w' is mounted a main shaft 2, on which is rotatably mounted a housing 3 provided with a lateral sleeve 4, said sleeve 95 extending substantially the full length of the shaft 2. Coiled in the housing 3 is a spring 5, the outer end of which is secured in any suitable manner to the peripheral wall of the housing 3, while the inner end is secured to the shaft 2. Mounted on the shaft 2 and confined between the wall w and outer

end of the sleeve 4 is a ratchet 6 adapted to be engaged by a spring-controlled pawl 7, and a winding key II is adapted to be screwed onto the end 2' of the shaft projecting from the casing B'.

Mounted on and securely fixed to the sleeve 4 near the outer end thereof is a driving gear 8, meshing with a pinion 9 mounted on a shaft 10. The end of the shaft 10 adjacent the wall w' terminates in a reduced portion 10' which portion has a bearing in said wall. The opposite end of the shaft 10 is provided with a socket m for receiving a stem s of an extension shaft 11, the stem being provided with a pin y, said pin extending into and traversing slots n, n, on opposite sides of the socket m of the shaft 10. Enveloping the stem s and confined between the shaft 10 and extension 11 is a coiled spring 12, which normally tends to force the extension 11 out of the casing B', however, such movement being limited by the pin y striking the ends of the slots n, n, (Fig. 3). The extension shaft 11 passes through the wall w', in which it has a suitable bearing, and is provided at its outer end with a polygonal portion 13 of reduced cross-section. The projection 13 is adapted to enter a socket o of corresponding shape in the adjacent end of the roller R', and by forcing the extension 11 slightly into the casing B', (which may be done by compressing the spring 12, the pin y traversing the slots n, n,) the spindle g on the opposite end of the roller R' is permitted to enter the bearing 1''.

The bracket B' is provided with a lateral extension or arm 14 through which the clamp C screws, and the inner faces f, f, of the bracket are lined with felt 15 or equivalent material to avoid marring the polished surfaces of the piano with which they come in contact. The clamp C is also faced with a similar material 15'. Corresponding faces f', f', of the casing B', and the clamp C', are lined similarly to the bracket B and clamp C.

Traversing the wall w' of the casing B' and mounted therein is a stem 16 provided at its outer end with a knob or head 17, and having a cam 18 mounted on its inner end contiguous to the peripheral wall of the housing 3. Secured to the inner portion of the stem 16 is a spring 19 whose free end is provided with a teat or button 20 of suitable formation adapted to enter one of a series of depressions 21 on the inside face of the wall w', upon turning the knob 17. By reason of the eccentricity of the cam 18 it may be brought to bear against the housing 3 by turning the knob to the right or it may be moved clear of the housing by turning the knob to the left (Fig. 5). The cam 18 is covered with felt, leather, or other yielding material z so any degree of pressure may be

brought to bear on the housing 3, thereby regulating the speed with which it can turn when the spring 5 unwinds.

In describing the operation of the invention let us assume that the roll S is being unwound from the roller R onto the roller R', the sheet moving in the direction indicated by the arrow (Fig. 2), whereupon any pointer or indicator strip p will drop onto one of the keys k of the piano when it reaches a certain point in the rotation of the roll (dotted position, Fig. 2), said strip continuing to rest on the key k during an interval depending on the length of the strip. Whichever keys are touched, and thus indicated to the operator, by the strips p, p', the operator will strike, and he will keep the key depressed as long as the strip bears on it. The strips may be of different lengths, such as p, p', on the right hand side of the roll (Fig. 8), the long fingers indicating a longer note than the short ones. i. e., the fingers p may designate half-notes and p' eighth-notes. When the attachment is used as an instructor the indicator strips may be marked by their proper letters corresponding to the note indicated, such as C, E, G, left hand, and Bb, E, right hand (Fig. 8); the fingers to be used may also be marked on the strips such as 5, 3, 1, left hand, and 1, 5, right hand, (Fig. 8). It is obvious that an unlimited amount of instruction notes and pointers may be placed on the roll S to assist the student, or guide an unskilled performer.

Rotation is imparted to the roll R' by the shaft 10 and extension 11, the pinion 9 on the shaft 10 being driven by the gear 8 mounted tightly on the sleeve 4 of the casing 3. The casing 3 is caused to rotate by the spring 5, which is fixed to the casing and shaft 2 as previously described, and tightly wound up by turning the key II in the direction indicated by the arrow (Fig. 4), said spring being prevented from unwinding by means of the ratchet 6 and pawl 7 as well understood in the art. However, the spring is free to unwind in the direction indicated by the arrow (Fig. 5) since the casing to which the outer end of the spring is secured is loosely mounted on the shaft 2. In unwinding the spring rotates the casing 5 at any desired speed, depending upon the pressure that is brought to bear on the periphery of the casing 5 by the cam 18, controlled by the operator by turning the knob 17. When the operator wishes to wind the spring he merely locks the casing by turning the knob 17 to the right. After the roll has been completely unwound from the roller R and wound onto the roller R' the rollers are reversed, the polygonal portion 13 of the extension 11 is inserted into a socket o' (similar to socket o in the end of roller R') in the end of roller R, the casing 3 is released and the roll rewinds onto the roller R. The roll

can now be removed and a new roll mounted in position over the keyboard of the piano.

The roll S must of course be as wide as the keyboard of the piano so that it may contain indicator strips for any or all, of the keys regardless of their location on the keyboard.

Obviously the present invention is susceptible of many modifications without departing from the spirit of the invention. Parts shown but not referred to are old in the art and need no particular description in this connection.

Having described my invention what I claim is:

1. In combination with a musical instrument provided with a keyboard, brackets fixed at each end of said keyboard, a pair of rollers mounted between said brackets, one of said rollers being positioned in close proximity to the keyboard and having a sheet or roll normally wrapped thereon, said roll being provided with suitable indicator strips, means for causing the roll to unwind from one roller and onto the other, whereby the said strips pass over the keyboard.

2. In combination with a musical instrument provided with a keyboard, an indicator roll mounted adjacent the keyboard, a roller mounted above the roll, means for causing the roll to unwind from itself and onto the roller, indicator strips on the roll, and adapted to bear momentarily on the keyboard during the unwinding of the roll.

3. In combination with the keyboard of a pianoforte, an indicator-roll positioned in close proximity to said keyboard, means for effecting an unwinding of the roll, and indicator strips on the roll, said fingers being adapted to bear on the keyboard during the unwinding of the roll.

4. A roll consisting of a sheet of suitable material, provided with indicator strips anchored at one end to said sheet and free to drop below the plane of said sheet on unwinding the roll.

5. A roll consisting of a sheet of suitable material, provided with indicator strips formed in the sheet and attached at one end thereto.

6. A roll consisting of a sheet of suitable material, provided with indicator strips punched therefrom and arranged so as to correspond to the notes of any musical composition.

7. In combination with the key-board and keys of a piano-forte, an indicator roll of sheet material provided with indicator strips partially cut out from the sheet and operating to fall below the level of the roll and to strike the keys, said strips being provided with characters to correspond with and identify the various keys of the keyboard.

8. In combination with a musical instru-

ment provided with a keyboard, a roller carrying a roll positioned over the keyboard, indicator strips on said roll, and means for causing an unwinding of the roll from the roller, whereby the strips of said roll are caused to come in contact with the keyboard.

9. In combination with a musical instrument provided with a keyboard, a roller carrying a roll positioned over the keyboard and in close proximity thereto, indicator strips on said roll, means for causing an unwinding of the roll from the roller whereby the strips of said roll are caused to come in contact with the keyboard, and means for regulating the speed of unwinding.

10. In combination with a musical instrument provided with a keyboard, a roller positioned over the keyboard and in close proximity thereto, an instruction roll normally wound on said roller, indicator strips on the instruction roll, a second roller spaced apart from the first roller, means for imparting rotation to the second roller, means for causing the instruction roll to wind onto the second roller from the first roller, whereby the strips on the roll engage the keyboard, and means for controlling the speed of winding.

11. In combination with the keyboard of a piano-forte, a bracket secured at one end of said keyboard, a bracket-casing secured at the opposite end of said keyboard, a roller provided with an instruction roll rotatably mounted between said bracket and bracket-casing, a second roller spaced apart from the first roller and rotatably mounted between the bracket and bracket-casing, said rollers being reversible with reference to one another, indicator strips on the roll, means for imparting rotation to the second roller, means for causing the roll to wind onto the second roller, whereby the strips engage the keyboard, and means for regulating the speed of winding.

12. In combination with the keyboard of a piano-forte, a bracket secured at one end of said keyboard, a bracket-casing secured at the opposite end of said keyboard, a roller rotatably mounted between said bracket and bracket-casing, an instruction roll normally wound on said roller, a second roller spaced apart from the first roller and rotatably mounted between the bracket and bracket-casing, said rollers being reversible with reference to one another, a shaft mounted in the bracket-casing provided with an extension movable along its axis through the inner wall of said casing, the extension being provided with a polygonal projection adapted to enter a correspondingly shaped socket in the adjacent end of the second roller, a pinion mounted on the aforesaid shaft, a main-shaft mounted in the casing, a housing provided with a lateral sleeve rotatably mounted on the main shaft, a spring in said housing having its ends secured respectively

to the housing and shaft, a driving gear mounted on the sleeve of the housing and meshing with the aforesaid pinion, means for winding the spring and means for controlling the unwinding thereof, whereby the housing is caused to rotate and impart rotation to the second roller.

In testimony whereof I affix my signature, in presence of two witnesses.
